UNITED STATES PATENT OFFICE.

JOSEPH BALOGH AND ANDREW THOMAS, OF CANAANVILLE, OHIO.

LIFE-BOAT.

1,112,667.

Specification of Letters Patent.

Patented Oct. 6, 1914.

Application filed December 2, 1913. Serial No. 804,156.

To all whom it may concern:

Be it known that we, JOSEPH BALOGH and ANDREW THOMAS, subjects of the King of Hungary, residing at Canaanville, in the county of Athens and State of Ohio, have invented certain new and useful Improvements in Life-Boats, of which the following is a specification.

This invention relates to certain new and useful improvements in life boats.

An object of the invention is to provide a life boat in which the entire hull constitutes an air chamber and wherein the top wall of the air chamber forms the deck for the passengers.

A further object of the invention is to provide a life boat in which the seats are disposed adjacent the side edges of the deck and arranging hand hold devices centrally of the deck between the rows of seats.

With the above and other objects in view which will appear as the nature of the invention is better understood, the same consists in the novel construction and arrangement of parts to be hereinafter more fully described and then claimed, reference being had to the accompanying drawing by like characters throughout the several views and wherein:—

Figure 1 is a side elevational view of our boat. Fig. 2 is a top plan view of the same, and Fig. 3 is an end elevational view.

Referring more specifically to the drawing, the reference numeral 10 designates the side walls of our boat and 11 the top wall or deck. It is to be noted that the space between the side walls 10 and top 11 constitutes an air chamber which holds the boat always in a buoyant position. The top wall 11 has a slight upward inclination from its connection with the side walls 10 to the longitudinal axis of the boat, which center line forms the highest part of the deck. Suitable oar locks 12 are carried by the sides of the boat and receive the usual oars 13 by which the boat is propelled.

Two rows of seats 14 are mounted upon the deck 11, one row upon either side of the center line thereof and substantially mid-way of the sides. Arranged centrally of the deck are the seats 15 which are to be used by the crew and positioned relative to the crew seats 15 are the boat holds 16. The

upper deck 11 is provided with an ordinary railing 17 which completely surrounds the same.

Hand hold means are provided and are designated in general 18, to be gripped by the passengers should the boat encounter a rough sea. These hand hold devices comprise more specifically the vertical shafts 19 connected by a longitudinal shaft 20, and it is to be noted that these hand hold devices are disposed centrally of the upper deck and between the two rows of seats. Depending from the longitudinal shafts 20 are the hand grips 21.

Our boat is provided with a keel 22 which is hingedly connected to the bottom of the boat as at 23 and is further provided with a rudder 24.

From the above description of our invention, it will be evident that by forming the entire hull structure of a buoyant body, that the same will always remain afloat and that by constructing the top wall or deck 11 with an inclination toward the center line thereof, that any water that may splash thereon will readily run off. It is further evident that by positioning the hand hold devices along the longitudinal axis of the boat intermediate of the several rows of seats, that the same may be readily gripped by the passengers.

While we have shown and described the preferred embodiment of our invention, we do not wish to confine ourselves thereto as various modifications and arrangements of parts may be had without departing from the spirit and scope of the invention as claimed.

What we claim as new is:—

A life boat comprising a buoyant hull, the deck of said boat forming the top wall of the hull, said deck inclined upwardly toward the longitudinal axis thereof, seats arranged along the inclined sides of the deck, and hand hold devices arranged along the longitudinal axis of the boat.

In testimony whereof we affix our signatures in presence of two witnesses.

JOSEPH BALOGH.
ANDREW THOMAS.
